UNITED STATES PATENT OFFICE.

EDGAR H. CLARK, OF NEW YORK, N. Y., ASSIGNOR TO WESTERN ELECTRIC COMPANY,
INCORPORATED, OF NEW YORK, N. Y., A CORPORATION OF NEW YORK.

CONTROLLING DEVICE.

1,334,735.

Specification of Letters Patent. Patented Mar. 23, 1920.

Application filed July 3, 1917. Serial No. 178,468.

To all whom it may concern:

Be it known that I, EDGAR H. CLARK, a citizen of the United States, residing at New York, in the county of New York and State of New York, have invented certain new and useful Improvements in Controlling Devices, of which the following is a full, clear, concise, and exact description.

This invention relates to signaling systems and more particularly to controlling devices employed in telephone systems.

The present invention has for its purpose the provision of a switching system responsive to impulses of various characteristics transmitted from a distant point, said system operating to selectively control the operation of automatic devices.

Other features not specifically pointed out will appear from the detailed description and appended claims.

The drawings, when arranged in accordance with the chart indicated in Figure 8, diagrammatically represent a portion of a telephone system employing the present invention.

In the system herein disclosed the apparatus associated with an A operator's position of a semi-automatic exchange and the apparatus associated with the B operator's position of a manual office are shown. It will be understood that only those parts are shown which are necessary for describing the establishment of a desired connection from a calling subscriber at A to the jack of a party line B.

In the present system the sequence switches are of the type disclosed in the patent to Reynolds and Baldwin 1,127,808, and are similar in operation and function to those disclosed in the patent to McBerly, 1,125,579.

The selective switches of this system may be of the type disclosed, in patent to Craft and Reynolds 1,123,696. The operating circuits for these switches are shown in the patent to Lundell 1,168,319.

In the present disclosure register, controlling devices and actuating relays are employed. The operation of these devices, except in so far as they are necessary for a clear understanding of this invention, has not been described. This operation is fully described in the above-mentioned patent to Lundell 1,168,319.

It is believed that the invention will best

be understood by describing the manner of establishing a connection from the calling subscriber whose substation is indicated at A, to the B operator, the method of indicating to the B operator the number of the desired line, and the method in which selective ringing current is applied to the called line.

When the calling subscriber removes his receiver from the switchhook, the line relay 102 is actuated in the well-known manner to light the lamp 103. The operator, on noting the lighting of lamp 103, inserts plug 104 in jack 105 of the calling line. A circuit is thereupon completed from grounded battery, winding of cut-off relay 106, sleeve of jack 105, sleeve of plug 104, winding of relay 107, to ground. The relays 106 and 107 are energized over this circuit. The cut-off relay 106 attracts its armatures to disconnect the line relay 102 from the calling line, and the line relay in turn extinguishes lamp 103. The relay 107, on attracting its armature, completes a circuit from ground, front contact and armature of relay 107, contact 108, magnet of sequence switch 100, to grounded battery, to move the sequence switch into position 2. As soon as the sequence switch 100 reaches position 2, a circuit is completed from grounded battery, magnet of sequence switch 200, contact 202, conductor 203, contact 109 to ground, to move the sequence switch 200 into position 2. In position 2 of sequence switch 200, an energizing circuit for the up-drive magnet 204 is closed from grounded battery winding of the up-drive magnet 204, contact 205, left-hand back contact and armature of relay 206 to ground. The up-drive magnet 204 controls the elevation of the cord finder generally designated 207. As soon as the brush 208 of the cord finder 207 engages terminal 209 associated with the cord circuit which has been connected to the calling line, the relay 206 is energized over a circuit which may be traced from grounded battery, winding of relay 206, contact 210, brush 208, terminal 209, conductor 211, contact 110, to ground. Relay 206 attracts its armatures and at its left-hand armature interrupts the operating circuit of the up-drive magnet 204, which circuit was previously described and at the right-hand armature and front contact of relay 206 a looking circuit is established for this relay from grounded battery, winding 110

of relay 206, contact 291; right-hand armature and front contact of relay 206, brush 212, terminal 213, conductor 214, contact 111, to ground, which maintains the relay 206 energized until the selector sequence switch 100 has moved out of position 11. At the left-hand armature and front contact of relay 206 a circuit is closed from ground, contact 215, magnet of sequence switch 200 to grounded battery, to move this sequence switch into position 3.

The operator thereupon places her headset (not shown) in telephonic communication with the substation apparatus and ascertains from the calling subscriber the number of the desired line. The operator then sets up this number on her key set, which is shown in Fig. 4 of the drawings. As soon as the operator has depressed the keys K^1, K^2, K^3, K^4, K^5 and K^6 , corresponding to the designation of the desired party, operating circuits for the registers 400, 401, 402, 403, 404 and 405 are completed. These registers then rotate to positions indicated by the depressed keys of the key set. The operating circuit for the register 400 extends from grounded battery, magnet of the register 400, right-hand armature and back contact of stop relay 406, conductor 407, contact 221, to ground. The operating circuits for the registers 401, 402, 403, 404 and 405 are similarly traced through the right-hand armature and back contact of the stop relays 408, 409, 410, 411 and 412, respectively, conductor 407, to ground at contact 221. As soon as the stop relays 406, 408, 409, 410, 411 and 412 are energized, a circuit is completed from ground through the left-hand armature and front contacts of these relays, conductor 413, contact 222, magnet of sequence switch 200 to grounded battery, to move the sequence switch out of position 3. Under the control of its master contact 223, sequence switch 200 rotates into position 6.

The fundamental circuit is now established from grounded battery, winding of the line relay 112, contact 113, conductor 114, terminal 216, brush 217, conductor 218, outer left-hand armature and back contact of the upper zero counting relay 219, winding of the stepping relay 220, contact 224, brush 225, terminal 226, conductor 227, contact 115 to ground. Relay 112 attracts its armature and thereby completes a locking circuit for itself. At the left-hand front contact and armature of relay 112 a circuit is also completed to move sequence switch 100 into position 3. With the sequence switch 100 in position 3 and with the line relay 112 energized, an operating circuit for the up-drive magnet 116 is completed from grounded battery, winding of magnet 116, conductor 117, contact 118, left-hand

armature and front contact of relay 112 to ground. Under the control of the up-drive magnet, a selector switch, generally designated 119, elevates its brushes and also elevates its commutator brushes 120 and 121. Each time that the commutator brush 120 encounters a conducting segment 122 of commutator 126, a circuit in shunt of the fundamental circuit just described is completed from ground, commutator brush 120, conducting segment 122, contacts 123 and 160, right-hand armature and front contact of relay 112, winding of the line relay 112 to grounded battery, to short-circuit the stepping relay 220 in the well-known manner. This short-circuiting operation of the stepping relay continues until the upper zero counting relay 219 of the chain of relays, the length of which is determined by the setting of the district register 400, is actuated. When the relay 219 attracts its armatures, at its outer armature and back contact it interrupts the fundamental circuit above described, and at its inner armature and front contact completes a circuit from ground, contact 228, magnet of sequence switch 200, to grounded battery, to move the sequence switch out of position 6 into position 7.

When the fundamental circuit was interrupted at the upper zero counting relay 219, the line relay 112 de-energized and at its left-hand back contact and armature completed a circuit from ground, contact 124, magnet of sequence switch 100 to grounded battery, to move this sequence switch out of position 3. Under the control of its master contact 101, sequence switch 100 continues to rotate until it reaches position 6. In position 6 of the sequence switch 100, an energizing circuit for test relay 125 is closed from grounded battery lower winding of relay 125, contact 127 to ground. The test relay 125 attracts its armatures and at its lower armature and front contact completes a circuit from ground through contact 128, magnet of sequence switch 100 to grounded battery, to move this sequence switch into position 7. In position 7 the test relay 125 is maintained energized over a circuit which may be traced from grounded battery, upper winding of the test relay, upper front contact and armature of relay 125, test brush 129 of the selector 119 to ground, over the test terminals of busy trunk lines. With the test relay 125 energized, an operating circuit for the up-drive magnet 116 is again completed from grounded battery, winding of the magnet 116, conductor 117, contact 130, lower front contact and armature of relay 125 to ground. As soon as the test brush 129 of the selector 119 encounters the test terminal of an idle line, which idle condition will be indicated by the absence of ground on the test terminal, the test relay 125 de-energizes and thereby completes a

driving circuit for driving the sequence switch 100 out of position 7. This circuit may be traced from grounded battery, magnet of sequence switch 100, contact 131, lower back contact and armature of test relay 125, to ground. Under the control of its master contact, the sequence switch rotates until it reaches position 11.

In position 7 of sequence switch 200, an operating circuit for moving the sequence switch 229 out of position 1 is closed from grounded battery, magnet of sequence switch 229, contacts 230, 231, to ground.

With the sequence switch 100 in position 11 and the sequence switch 200 in position 7, a circuit is completed from grounded battery, right-hand winding of relay 302, left-hand armature and back contact of relay 303, conductor 304, repeating coil 305, lower inner armature and back contact of relay 301, ring conductor 137 of the trunk, terminal 134, brush 135, contact 136, conductor 227, terminal 226, brush 225, contact 233, contact 234, winding of relay 235, to ground.

The relays 235 and 302 are energized over this circuit and attract their armatures. At the front contact and armature of the relay 235 a circuit is completed from ground, contact 236, magnet of sequence switch 229 to grounded battery, to move the sequence switch 229 out of position 2 into position 3.

Upon the energization of the relay 302, a circuit is completed for lighting lamp 306 after the calling line has been extended to the operator's position. The actuating circuit of lamp 306 may be traced from grounded battery, conductor 307, armature and front contact of relay 302, conductor 308, outermost back contact and armature of relay 309, resistance 310 to ground. The operator, on noting the lighting of lamp 306, depresses the key 311, whereupon a circuit is completed from ground, winding of relay 301, key 311, conductor 312, winding of slow releasing relay 2, to grounded battery. The relays 2 and 301 are energized over this circuit and attract their armatures. The relay 2 at its armature and front contact applies ground to various controlling leads shown in Fig. 5.

When the relay 301 attracted its armatures the controlling circuit of the relay 235, which is extended over conductor 313, was open at the left-hand armature and front contact of relay 10. The relay 235 deenergizes and at its back contact and armature completes a circuit from ground through contact 237, magnet of sequence switch 239, to grounded battery. The sequence switch 239 rotates out of position 3 and continues to rotate through its various positions back to position 1 under the control of its master contact 238.

After relay 301 attracted its armatures

and while sequence switch 239 is moving through positions 3 $\frac{1}{2}$ to 4, a circuit was established from grounded battery, winding of the relays 6 and 5, conductor 314, inner front contact and upper armature of relay 70 301, conductor 138, terminal 139, brush 132, contact 133, conductor 114, terminal 216, brush 217, conductor 218, contact 232, to ground. The impulse transmitted in this last described circuit may be termed a "pick-up" impulse and serves to place the impulse recording device in condition to receive the number indicating impulses, as will be pointed out.

The operation of the relays 7 and 8 and the operation of the switching relays 18, 15, 29, 18, 31, 19 and 33, which are controlled by the relays 7 and 8, may be described as follows: In response to the pick-up impulse the relay 6 is energized and at its right-hand front contact and armature completes a circuit traceable from grounded battery, right-hand or holding winding of the relay 7, winding of relay 8, left-hand back contact and armature of relay 7, right-hand front contact and armature of relay 6, to ground over conductor 9. The relay 8 attracts its armatures and at its right-hand armature and front contact completes a circuit from ground, back contact, armature and winding of relay 10, to grounded battery. The relay 10 attracts its armatures and establishes a locking circuit for itself which is completed from grounded battery, winding of relay 10, right-hand armature and contact spring 11 100 of this relay, left-hand back contacts and armature of relay 17 to ground over conductor 3. At its left-hand front contact and armature, the relay 8 prepares a circuit for energizing the left-hand or pull up winding of the relay 7. This last mentioned winding, however, is short-circuited as long as the relay 6 maintains its armatures attracted in response to the pick-up impulse. At the close of the pick-up impulse both windings 110 of the relay 7 are energized over a circuit traceable from grounded battery, right-hand winding of relay 7, winding of relay 8, left-hand winding of relay 7, left-hand front contact and armature of relay 8, to ground over conductor 9. At this time the station's switching relay 18 has its energizing circuit completed at the right-hand front contact and armature of relay 7, as will be more fully described. In response to the station's 120 impulses, either or both of the relays 6 and 12 will be energized, whereupon the right-hand or holding winding of the relay 7 will be energized from grounded battery, right-hand winding of this relay, left-hand front contact and armature of relay 7, through the right-hand front contact and armature of relay 6, or the left-hand front contact and armature of relay 12, to ground over conductor 9. The relay 8 will be short-circuited 125

130

at this time and retracts its armatures. At the close of the station's impulses the armatures of both relays 6 and 12 will be attracted and the relay 7 will be deenergized to complete at its right-hand armature and back contact a circuit for the thousands switching relay 15. In response to the thousands impulses either the relay 6 or the relay 12 will be operated, whereupon the cycle of 5 operation of the relays 7 and 8 will begin again. In other words, the relay 8 will be energized over a circuit now traceable from grounded battery, right-hand winding of relay 7, winding of relay 8, left-hand back contact and armature of relay 7, through the right-hand front contact and armature of relay 6 or the left-hand armature and back contact of relay 12, to ground over conductor 9. The relay 8 attracts its armatures and 10 when the thousands series of impulses has terminated and the relays 6 and 12 are inert, the circuit for the left-hand or pull-up winding of relay 7 will be from grounded battery, right-hand winding of relay 7, winding 15 of relay 8, left-hand winding of relay 7, left-hand front contact and armature of relay 8 to ground over conductor 9. With the armatures of the relay 7 attracted a circuit is completed at the right hand front contact of 20 relay 7 for energizing the switching relay 29. In response to the thousands and hundreds translation impulses, the relays 6 and 12 will be operated again and a circuit will be completed from grounded battery through the 25 right-hand winding of relay 7, left-hand front contact and armature of relay 7, through the right-hand front contact of relay 6, or the left-hand front contact and armature of relay 12, to ground over conductor 9. This operation serves to short-circuit relay 8. At the close of this series of 30 impulses the circuit holding winding of relay 7 is interrupted either at the armature and contact of relay 6 or at the armature and contact of relay 12. At the right-hand back contact and armature of relay 7 an energizing 35 circuit for the hundreds switching relay 18 is completed. The cycle of operation of the relays 7 and 8 will be completed for 40 the relays 31, 19 and 33. At the end of the hundreds series of impulses the relay 7 will be energized to complete a circuit for the tens switching relay 31; at the end of the tens series of impulses the relay 7 will be de- 45 energized to complete a circuit for the tens and units translation switching relay 19; and at the end of the tens and units translation series of impulses the relay 7 will be energized to complete a circuit for the units 50 switching relay 33.

As soon as the relay 7 attracted its armatures in response to the pick-up impulse, a circuit was completed for energizing a station switching relay 13. This circuit is 55 completed from grounded battery, winding

of relay 13, armature and back contact of relay 14, inner right-hand armature and back contact of relay 15, conductor 16, inner right-hand armature and back contact of relay 18, inner right-hand armature and back 60 contact of relay 19, conductor 20, right-hand front contact and armature of relay 7, to ground over conductor 3. The relay 13 attracts its armatures and at its inner left-hand contact closes a locking circuit for 65 itself through contacts and contact springs 35, 36, 37, 38, 39, 40, conductors 41, 9 and 3 to ground. *Sequence switch 229*

When the sequence switch 229 reached position 4 a circuit was completed from 80 grounded battery, magnet of sequence switch 200, contacts 270 and 271 to ground to move this sequence switch into position 8. While the sequence switch 229 is rotating through its various positions in proper sequence, it 85 closes its contacts (shown at the right-hand corner of Fig. 2) to control the transmission of the impulses which cause the automatic selection of the proper ringing current of the desired subscriber on the party line, and 90 also transmits impulses for actuating the proper group of relays which control the setting up of the indication of the desired subscriber's number. The character of these impulses is controlled by the length of closure of the contacts of sequence switch 229. Impulses of three different characters may be transmitted over the tip and ring conductors of the selected trunk. These impulses may be described as being long, short 100 and medium in length. For convenience, the long impulse may be said to consist of early, middle and late closure of the contacts leading to the tip or ring conductors. The short impulse may consist either of 105 an early, middle or a late closure of these contacts; while the medium length impulse may consist of an early and a middle closure, or a middle and a late closure of these contacts. For convenience in describing the 110 selection of ringing current, for the actuation of the relays which control the setting up of the desired subscriber's number, the terms "early", "middle" and "late" will be used to describe the character of the impulse employed in these operations. *115*

Let it be assumed that the desired subscriber's number is 9987-W. Under this assumption the operator in setting up the number on the keyboard has caused the 120 thousands register 401 to stop in position 9, the hundreds register 402 in position 9, the tens register 403 in position 8, the units register 404 in position 7 and the stations register 405 in position 4. In order to select 125 the proper ringing current for ringing party W, it is necessary to lock up the relays 21, 22 and 28 of Fig. 5. To accomplish this, it is necessary to transmit the following code impulses: a middle impulse 130

on the tip conductor, and early, middle and late impulses on the ring conductor. With this setting of the station's register 405 while the sequence switch 229 is rotating through 5 positions 4 $\frac{1}{2}$ to 5 $\frac{1}{2}$, a circuit is completed from ground, contact 239, conductor 240, contact 415, conductor 416, contacts 241, 233, brush 225, terminal 226, conductor 227, contact 136, brush 135, terminal 134, ring conductor 137, lower inner armature and front contact of relay 301, conductor 313, left-hand front contact and armature of relay 10, winding of relay 12, to grounded battery. While the sequence switch 229 is rotating 10 through position 5 to 5 $\frac{1}{2}$, a circuit is closed from ground, contact 242, conductor 243, contact 417, conductor 418, contact 244, conductor 218, brush 217, terminal 216, conductor 114, contact 133, brush 132, terminal 139, tip conductor 138, upper inner armature and front contact of relay 301, conductor 314, windings of relays 5 and 6, to grounded battery. While the sequence switch 229 is passing through position 5 to 5 $\frac{1}{2}$, a circuit is closed from ground, contact 245, conductor 246, contact 419, conductor 416, contacts 241 and 233, brush 225, terminal 226, conductor 227, contact 136, brush 135, terminal 134, conductor 137, inner lower armature and front contact of relay 301, conductor 313, left-hand front contact and armature of relay 10, winding of relay 12, to grounded battery.

It will thus be seen that the first station's impulse sent is transmitted over the ring conductor to energize the relay 12. With the relay 12 energized, an energizing circuit is completed for the relay 21, which in part controls the lighting of the station's lamp. This relay is energized from grounded battery, right-hand winding of relay 21, right-hand back contact and armature of relay 22, conductor 23, outer left-hand armature and contact of relay 13, conductors 24 and 25, back contact and left-hand armature of relay 6, right-hand front contact and armature of relay 12, conductor 9, to ground at the armature of relay 2. Relay 21 attracts its armature and at its 40 inner left-hand front contact and armature establishes a locking circuit for itself through both of its windings in series to ground over conductor 9. In response to the middle impulses, the relays 5, 6 and 12 45 are energized. With these relays energized, the relay 22 is operated over a circuit traceable from grounded battery, right-hand winding of this relay, conductor 26, outer right-hand front contact and armature of relay 13, conductor 27, contact and armature of relay 5, right-hand front contact and armature of relay 12, conductor 9, to ground at the armature of relay 2. The relay 22 attracts its armatures and establishes a 50 locking circuit for itself which is completed

from grounded battery through both windings in series of this relay, its inner left-hand front contact and armature, conductors 9 and 3 to ground at the armature of relay 2. In response to the late impulses 55 the relay 12 is energized and thereby completes an energizing circuit for the relay 28 which extends from grounded battery, right-hand winding of this relay, right-hand front contact and armature of relay 22, conductor 23, outer left-hand front contact and armature of relay 13, conductors 24 and 25, left-hand back contact and armature of relay 6, right-hand front contact and armature of relay 12, conductors 9 and 3, to ground at the armature of relay 2. The relay 28 attracts its armatures and establishes a locking circuit for itself through both windings in series, its inner left-hand front contact and armature, over conductors 9 and 3, to ground at the armature of relay 2. The relay 28 attracts its armatures and establishes a locking circuit for itself through both windings in series, its inner left-hand front contact and armature, over 60 conductors 9 and 3, to ground at the armature of relay 2. At the close of this series of impulses, the relays 6 and 12 are deenergized which interrupts the holding circuit of the relay 7, permitting this relay to retract its armatures. It will be remembered as soon as the relay 13 attracted its armatures, a break point in the series circuit for relays 14 and 15 was closed. When now relay 7 retracts its armatures at the close of the series of impulses, the 65 energizing circuit for relay 14 is completed from grounded battery winding of relay 14, winding of relay 15, inner right-hand front contact and armature of the relay 13, inner right-hand back contact and armature of relay 29, conductor 30, inner right-hand back contact and armature of relay 31, conductor 32, inner right-hand back contact and armature of relay 33, conductor 34, right-hand back contact and armature of relay 7, to ground over the conductor 3. The relays 14 and 15 are energized in this 70 circuit. The relay 14 at its armature and back contact interrupts the original energizing circuit of the relay 13. The relay 15 at its inner left-hand armature and spring 35 interrupts the locking circuit of relay 13 and also completes a locking circuit for itself traceable from grounded battery, windings of relays 14 and 15 in 75 series, inner left-hand armature and contact spring 35 of relay 15, contact and contact springs 36, 37, 38, 39, 40, conductors 41, 9 and 3 to ground. It will be understood that the relay 15 also closes a break point in the circuit for transmitting the thousands 80 series of impulses to the relays controlling the lighting of the thousands lamps.

It has not been deemed necessary to describe the transmission of the impulses for 85 operating the No. 9 thousands lamp. It is believed that it will be understood that with the thousands impulse register set in position 9 that the following code impulses will be sent: a middle impulse over the tip con- 90

ductor, and an early, middle and late impulse over the ring conductor. In response to an early impulse over the ring conductor the relay 12 is energized to complete a circuit from ground, conductors 3 and 9, right-hand armature and front contact of relay 12, left-hand armature and contact of relay 6, conductor 25, outer right-hand armature and front contact of relay 15, conductor 520, left-hand winding of relay *a*, outer armature and back contact of relay *c*, to grounded battery. The relay *a* is energized in this circuit and establishes a locking circuit for itself which may be traced from grounded battery, outer contact and armature of relay *c*, both windings of relay *a* in series, right-hand inner front contact and armature of relay *a*, conductor 539, conductor 3, to ground. While the middle impulses are being transmitted, the relays 5, 6 and 12 are energized. With these relays energized a circuit is completed from ground, conductors 3 and 9, right-hand armature and front contact of relay 12, armature and front contact of relay 5, conductor 27, outer left-hand armature and front contact of relay 15, conductor 525, left-hand winding of relay *b*, outer left-hand armature and front contact of relay *c* to grounded battery. The relay *b* attracts its armatures and completes a locking circuit for itself from grounded battery, outer left-hand armature and back contact of relay *c*, both windings of relay *b* in series, right-hand inner front contact and armature of relay *b* to ground over conductor 539, as previously described. In response to the late impulse, only the relay 12 is energized. This completes a circuit from ground over the conductors 3 and 9, right-hand armature and front contact of relay 12, left-hand armature and back contact of relay 6, outer right-hand contact and armature of relay 15, conductor 520, outer left-hand armature and front contact of relay *b*, left-hand winding of relay *c*, to grounded battery. Relay *c* attracts its armatures and thereby establishes a locking circuit for itself and also interrupts the holding circuits of relays *a* and *b*. At the close of the thousands series of impulses the relays 5, 6 and 12 deenergize and the relays 7 and 8 become energized. With relay 7 energized a circuit is completed from grounded battery, windings of relays 14 and 29 in series, inner right-hand front contact and armature of relay 15, conductor 16, inner right-hand armature and back contact of relay 18, inner right-hand back contact and armature of relay 19, right-hand front contact and armature of relay 7, conductor 3 to ground. Relays 14 and 29 are then maintained energized in a series circuit from grounded battery, inner left-hand armature and contact springs 36 of relay 29, contacts and contact springs 37,

38, 39, 40, conductors 41, 9 and 3 to ground. The relay 29, by attracting its armatures, controls the transmission of the impulses controlling the translation at the relays effecting the thousands and hundreds number-indicating lamps. 70

The thousands impulses which have just been transmitted have been sufficient to select the thousands lamps 8 and 9. It is now necessary to transmit impulses to select the No. 9 lamp. By noting the code shown on Fig. 7, it will be seen that since the number 9 is an odd number, and since it occurs in the second five hundred of the odd thousands, an early, middle and late impulse will be sent over the tip conductor, and a middle impulse over the ring conductor of the selected trunk. These impulses are transmitted in accordance with the translation which takes place, as will be indicated by tracing the following circuits. 80

In response to the early impulse of the series controlling the thousands translation, only the relays 5 and 6 are energized, and since the relay 12 is not energized, neither the relays *a*² or *b*² will be energized. But in response to the middle impulse, the relays 5, 6 and 12 will be energized, and since the relay 29 is already energized, a circuit is completed from ground, conductors 3 and 9, right-hand armature and front contact of relay 12, armature and front contact of relay 5, outer right-hand armature and front contact of relay 29, conductor 527, winding of relay *b*², to grounded battery. 100 The relay *b*² attracts its armatures and completes a locking circuit from grounded battery, windings of relay *b*² in series, inner right-hand front contact and armature of relay *b*², to ground over conductor 539, as described. In response to the late impulse, only the relays 5 and 6 are energized. For this reason no further energizing circuit is completed for the thousands controlling relays in Fig. 7. At the close of this series of impulses the relay 7 deenergizes. This completes an energizing circuit for the relay 18 extending from grounded battery, winding of the relay 14, winding of relay 18, inner right-hand front contact and armature of relay 29, conductor 30, inner back contact and armature of relay 31, conductor 32, inner right-hand back contact and armature of relay 33, conductor 34, armature and back contact of relay 7, conductor 3, to ground. 110 Relay 18 by attracting its armatures causes the deenergization of relay 29 and establishes a locking circuit for relays 14 and 18 through contact springs 38, 39 and 40, conductors 41, 9 and 3 to ground. 120

For selecting the No. 9 hundreds lamp, the middle impulse is transmitted over the tip conductor and an early, middle and late impulse over the ring conductor of the trunk selected. It is not deemed necessary to trace 130

circuits in which these impulses are transmitted through the contacts of sequence switch 229. It will be assumed that these various impulses are transmitted to actuate the relays 5 and 6 and 12. Since an early impulse is first transmitted over the ring conductor, only the relay 12 will be energized, as a result of which an energizing circuit is completed from ground, at the armature and contact of relay 2, conductors 3 and 9, right-hand armature and front contact of relay 12, armature and back contact of relay 6, conductor 25, outer right-hand armature and front contact of relay 18, conductor 529, 5 left-hand winding of relay a^1 , outer left-hand armature and back contact of relay c^1 , to grounded battery. Relay a^1 attracts its armatures and locks itself up to ground over conductor 539. The middle impulse is 10 then transmitted over both the tip and ring conductors, as a result of which the relays 5, 6 and 12 are energized. This completes a circuit from ground over conductors 3 and 9, right-hand armature and front contact of 15 relay 12, armature and front contact of relay 5, conductor 27, outer left-hand armature and front contact of relay 18, conductor 531, left-hand winding of relay b^1 , outer left-hand armature and back contact of relay a^1 , 20 to grounded battery. Relay b^1 locks itself up to ground over conductor 539. During the transmission of the late impulses, only a late impulse is transmitted over the ring conductor, thus only the relay 12 is energized. This relay, by attracting its armature, closes an energizing circuit from 25 ground, over conductors 3 and 9, right-hand front contact and armature of relay 12, left-hand armature and back contact of relay 6, conductor 25, outer right-hand armature and front contact of relay 18, conductor 529, outer left-hand armature and front of relay b^1 , left-hand winding of relay c^1 , to grounded battery. The relay c^1 is energized in this 30 circuit and attracts its armatures and at its outer left-hand back contact and armature interrupts the energizing circuits of relays a^1 and b^1 . The relay c^1 , in operating, attracts its armatures and completes a holding 35 circuit for itself over the conductor 539. At the close of this series of impulses, the relay 7 is energized and a circuit is completed for the relay 31 which controls the transmission of impulses to the relays which light the 40 tens lamp. The relay 31 is energized over a circuit which is traceable from grounded battery, windings of relays 14 and 31, inner right-hand front contact and armature of relay 18, inner right-hand armature and back contact of relay 19, conductor 20, right-hand front contact and armature of relay 7, to ground over conductor 3. Relay 31 attracts its armatures and at contact spring 45 38, breaks the holding circuit of the actuated relays preceding it in the series and locks 50

itself to ground through springs 38, 39 and 40, over conductors 41, 9 and 3.

For selecting the No. 8 tens lamp, a middle impulse is transmitted over the tip conductor, and an early, middle and late impulse over the ring conductor of the selected trunk. Since an early impulse is transmitted over the ring conductor and no early impulse is transmitted over the tip conductor, relay 12 is energized and the relays 5 and 6 remain deenergized. Under these conditions a circuit is closed extending from ground over conductors 3 and 9, right-hand armature and front contact of relay 12, left-hand armature and back contact of relay 6, conductor 25, outer left-hand armature and front contact of relay 31, conductor 533, left-hand winding of relay A^{10} , outer left-hand armature of relay C^{10} , to grounded battery. The relay A^{10} locks itself to ground over conductor 539. The middle impulses are then transmitted over the tip and ring conductors to energize the relays 5, 6 and 12. With this combination of relays actuated, a circuit is closed from ground over conductors 3 and 9, right-hand armature and front contact of relay 12, armature and front contact of relay 5, conductor 27, outer right-hand armature and front contact of relay 31, conductor 535, left-hand winding of relay B^{10} , outer left-hand armature and back contact of relay C^{10} , to grounded battery. The relay B^{10} locks itself to ground over conductor 539. A late impulse is now transmitted over the ring conductor, but no late impulse is transmitted over the tip conductor of the selected trunk. Relay 12 is energized; but relays 5 and 6 are inert. Under these conditions a circuit is closed from ground over conductors 3 and 9, right-hand armature and front contact of relay 12, left-hand armature and back contact of relay 6, conductor 25, outer left-hand armature and front contact of relay 31, conductor 533, outer left-hand armature and front contact of relay B^{10} , left-hand winding of relay C^{10} , to grounded battery. The relay C^{10} attracts its armature and at its outer left-hand armature and back contact interrupts the holding circuit of the relays A^{10} and B^{10} . The relay C^{10} in operating also closes a locking circuit for itself. The last mentioned impulses are sufficient to select the Nos. 8 and 9 tens lamps. At the close of this series of impulses the relay 7 retracts its armatures and thereby completes a circuit for energizing relay 19. This circuit extends from grounded battery, windings of relays 14 and 19 in series, inner right-hand front contact and armature of relay 31, conductor 32, inner right-hand front contact and armature of relay 33, conductor 34, right-hand back contact and armature of relay 7, to ground over conductor 3. Relay 19 by attracting its armatures interrupts the

holding circuit of relay 31 and establishes a locking circuit for itself through contacts 39 and 40, conductors 41, 9 and 3 to ground.

It is now necessary to transmit impulses

- 5 to select the No. 8 tens lamp. Since the numeral 8 is in the second group of even tens, it is necessary to transmit an early and a middle impulse over the tip conductor, and a middle and late impulse over the ring conductor. Since no early impulse is transmitted over the ring conductor, the relay 12 is not energized. In response to the middle impulses, the relays 5, 6 and 12 are again energized. This prepares an energizing circuit from ground over conductors 3 and 9, right-hand armature and front contact of relay 12, armature and front contact of relay 5, conductor 27, outer left-hand armature and front contact of relay 19, conductor 15 537, left-hand winding of relay B^2 , to grounded battery. Relay B^2 in energizing establishes a locking circuit for itself to ground over 539. In response to the late impulse, the relay 12 is energized, which in 20 turn controls the energization of the relay A^2 over a circuit traceable from ground over conductors 3 and 9, right-hand armature and front contact of relay 12, left-hand armature and back contact of relay 6, conductor 25 25 25, outer right-hand armature and front contact of relay 19, conductor 575, winding of relay A^2 , to grounded battery. The relay A^2 attracts its armatures and establishes a locking circuit for itself over conductor 30 35 539.

Since the relay 7 remains energized at the close of the last series of impulses, an energizing circuit is completed from grounded battery, windings of relays 14 and 33, inner 40 right-hand front contact and armature of relay 19, conductor 20, right-hand front contact and armature of relay 7 to ground over conductor 3. The relay 33 attracts its armature and establishes a locking circuit for 45 itself through its inner armature and contact spring 40 to ground over conductor 41.

For selecting the units lamp No. 7, an early, middle and late impulse is transmitted over the tip conductor, and a middle impulse over the ring conductor. Since no early or late impulses are transmitted over the ring conductor, the relay 12 is not energized and therefore completes no energizing circuit for operating the relays controlling 55 the lighting of the units lamps. However, middle impulses are transmitted over the tip and ring conductors to energize the relays 5, 6 and 12. Under these conditions a circuit is closed from ground over the conductors 3 and 9, right-hand armature and front contact of relay 12, armature and front contact of relay 5, conductor 27, outer right-hand armature and front contact of relay 33, conductor 580, left-hand winding of relay 60 65 B^1 , outer left-hand armature and back con-

tact of relay C^1 , to grounded battery. Relay B^1 attracts its armatures and thereby establishes a locking circuit for itself over conductor 539.

As soon as the relay 18 attracted its armatures a circuit was completed for energizing the relay 42; and this relay by attracting its armatures completes circuits for lighting the various number-indicating lamps. The relay 42 is initially energized over a circuit 70 extended from grounded battery, left-hand winding of this relay, inner right-hand front contact and armature of the relay 18, inner right-hand back contact and armature of the relay 19, conductor 20, right-hand front 75 contact and armature of relay 7, conductor 3 to ground. The relay 42 when once energized maintains itself actuated through its right-hand winding through resistance 579 to ground over conductors 9 and 3, and when 80 relay 33 attracts its armatures the relays 17, 44 and 45 are energized in parallel over circuits traceable from grounded battery to the windings of these relays through the inner right-hand front contact and armature of 85 relay 33, conductor 34, right-hand back contact and armature of relay 7 to ground over conductor 3. It will thus be seen that the thousands and hundreds lamps are simultaneously lighted and that at a subsequent 90 point the tens, units and stations lamps are lighted. The circuit for lighting the No. 9 thousands lamp may be traced from grounded battery, inner right-hand armature and contact of relay 42, conductor 542, outer left- 95 hand armature and back contact of relay a^2 , inner left-hand armature and back contact of relay b , outer right-hand armature and back contact of relay a , inner left-hand armature and front contact of relay c , through 100 the No. 9 thousands lamp, outer right-hand front contact and armature of relay c , conductor 543 to ground at the outer left-hand contact and armature of relay 42 to ground. The circuit for lighting the No. 9 hundreds 105 lamp is completed from grounded battery, outer right-hand armature and front contact of relay 42, conductor 546 through the No. 9 hundreds lamp, inner left-hand front contact and armature of relay c' , outer right- 110 hand back contact and armature of relay a' , inner left-hand back contact and armature of b' , inner right-hand front contact and armature of relay b^2 , conductor 539 to ground.

It will be remembered that the following 115 relays of Fig. 6, controlling the lighting of the tens and units indicating lamps, have been actuated and locked up, C^{10} , A^2 , B^2 and B^1 . With these relays actuated, a circuit is closed for lighting the No. 8 tens 120 lamp; this circuit is traceable from grounded battery, right-hand armature and contact of relay 45, conductor 548, through the No. 8 tens lamp, inner left-hand front contact and armature of relay C^{10} , outer right-hand back 125 130

contact and armature of relay A¹⁰, inner left-hand back contact and armature of relay B¹⁰, inner right-hand front contact and armature of relay A², conductor 539 to ground. The circuit for lighting the No. 7 units lamp extends from grounded battery, right-hand armature and contact of relay 45, conductor 550, lamp No. 7, inner left-hand armature and back contact of relay A', 10 inner left-hand armature and front contact of relay B', inner right-hand front contact and armature of relay B², conductor 539 to ground.

The circuit for lighting the W station's lamp extends from grounded battery, right-hand armature of relay 44 and contact 46, station's lamp W, right-hand front contact and armature of relay 28, outer left-hand front contact and armature of relay 21, 20 outer left-hand front contact and armature of relay 22, left-hand front contact and armature of relay 17 to ground over conductor 3.

When sequence switch 229 returns to position 1 after rotating through its various positions to transmit the code impulses, a circuit is completed for moving the sequence switch 100 out of position 11 and into position 16. This circuit may be traced from ground, contacts 276 and 275, brush 274, contact 273, contact 150, magnet of sequence switch 100, to grounded battery. The sequence switch 100, by rotating to position 16, closes its contacts 175 and 176 to close break points in the conversational circuit. As soon as the sequence switch 100 rotates out of position 11, the relay 206, whose locking circuit was completed at the contact 111, retracts its armatures. At the 40 left-hand armature and back contact of relay 206, a circuit is completed from ground through contact 260, magnet of sequence switch 200, to grounded battery. The sequence switch 200 rotates into position 18 in which position a circuit is completed for down-drive magnet 261, from grounded battery, winding of the magnet, contact 262, to ground. Under the control of the down-drive magnet, the cord selector 207 restores 45 to its normal position. When this takes place, a circuit is closed from ground, contacts 264 and 263, winding of motor magnet of the sequence switch 200, to grounded battery. This circuit moves the sequence switch into its normal position.

The operator, on noticing the number of the desired line set up on the call indicating lamps, inserts a plug 316 into the jack 317 of the party line over which the desired 50 subscriber can be reached and releases key 311. The release of this key causes the restoration of the number indicating apparatus and also causes the deenergization of the relay 301. Relays 300 and 302 become 55 energized and attract their armatures. As

soon as the plug 316 is inserted into the jack 317, a circuit is completed from grounded battery, through the lamp 306, winding of the relays 309, 318, sleeve of plug 316, sleeve of jack 317, winding of relay 319, to ground. The relays 309 and 318 attract their armatures. It will be understood that the lamp 306 is shunted at this time. As soon as the relay 309 attracts its armatures, a circuit is prepared for the relay 320, which extends from grounded battery, winding of the relay 320, armature and back contact of relay 321, back contact and armature of relay 322, outer left-hand front contact and armature of relay 309, conductor 308, armature and contact of relay 302, to ground through relays 309, 318 and 319. The relay 320 is energized in this circuit and attracts its armatures. Simultaneously with the energization of the relay 320, the relay 303 is actuated over a circuit traceable from grounded battery, winding of relay 303, inner armature and front contact of relay 309, resistance 310, to ground. The relay 303 attracts its armatures. The relays 323 and 324 were actuated as soon as the relays controlling the station's lamps were operated. The relay 323 was energized over a circuit closed from grounded battery, winding of relay 323, conductor 325, the lower armature and front contact of relay 301, conductor 326, resistance 551, right-hand front contact and armature of relay 28, outer left-hand front contact and armature of relay 21, outer left-hand front contact and armature of relay 22, armature of relay 17 to ground. The relay 324 is energized over a circuit completed from grounded battery, winding of relay 324, conductor 327, outer upper armature and front contact of relay 301, conductor 328, outer left-hand front contact and armature of relay 21, outer left-hand front contact and armature of relay 22, left-hand front contact and armature of relay 17 to ground over conductor 3. These relays, as soon as they were energized, were locked up through contact spring 329, conductor 523, resistance 522, conductor 3 to ground. As soon as the relay 303 attracted its armatures the following locking circuits were substituted for the circuits previously traced for the relays 323 and 324. The locking circuit of relay 323 is traceable from grounded battery, winding of relay 323, 110 left-hand armature and front contact of this relay, contact 329, right-hand armature and front contact of relay 303, to ground. The locking circuit of the relay 324 extends from grounded battery, winding of relay 324, right-hand armatures and front contact of relay 324, contact spring 329, armature of the relay 303, to ground.

In order to prevent the ringing of a substation set other than that of the desired 130

party, when the plug 316 is being inserted into jack 317, an interrupting device 330 is provided. This interrupter is of the well-known type which consists of a constantly 5 rotating shaft on which are secured the disks 331, 332 and 333. The disks 332 and 333 are insulated from the shaft on which they are secured and are provided with brushes which engage their peripheries. 10 The periphery of the disk 331, with the exception of a very small portion, is covered with an insulating material. The conducting portion is so positioned with respect to the conducting portions of the disks 332 and 333 that while a circuit is completed 15 through the disk 331, no circuit is completed through the disks 332 and 333. The purpose of this adjustment will be hereinafter described. 20 After the insertion of the plug 316 into the jack 317 and after the energization of the relay 318, as soon as the brush of the disk 331 encounters its conducting segment, a circuit is completed from grounded battery through the disk 331 and its brush, 25 through the contact and contact spring 334, through the winding of the relay 335, lower armature of the relay 318, contact spring 336, right-hand contact and armature of relay 324, to ground at contact spring 329 and 30 armature of relay 303. The relay 335 attracts its armature and completes a circuit from grounded battery through the contact spring 334, over the circuit just described. 35 When now the brush of the disk 333 encounters its conducting segment, a circuit is completed from the positive source of ringing current 337, conducting portion and brush of disk 332, left-hand winding of the relay 322, right-hand front contact and 40 armature of relay 323, left-hand front contact and armature of relay 335, upper front contact and armature of relay 320, upper armature and upper contact of relay 318, 45 tip of plug 316, tip of jack 317, through the substation apparatus of the desired subscriber, ring of jack ring of the plug, lower armature and front contact of the relay 320, left-hand armature and front contact 50 of relay 324 to ground.

The relay 322 is marginal and does not attract its armatures until the called subscriber has answered. When the relay 322 is energized, the relay 321, which was 55 shunted, attracts its armatures and completes a circuit from grounded battery, left-hand armature and front contact and winding of the relay 321, outer left-hand front contact and armature of relay 309, armature and front contact of relay 302, windings of the relays 309, 318 and 319, to 60 ground. The relay 321 locks itself up in this circuit and prevents the reapplication of ringing current. 65 When at the close of the conversation the

A operator restores the selector switch 119, after noting the replacement of the receiver on the switchhook of the calling station, the supervisory lamp 306 operates in the well-known manner to inform the B operator that the call has terminated, whereupon she removes plug 316 from jack 317 to deenergize the relays 309, 318, and 319. The relay 309, in deenergizing, causes the deenergization of relay 303, and this relay 70 interrupts the locking circuit of the relays 323, 324 and 335. Relay 338 is provided to prevent a second series of impulses from actuating the call-indicating apparatus until the B operator has removed the 80 plug 316 from the jack 317.

When the B operator noted the number indicated she released key 311, which causes the relays 301 and 2 to deenergize. Relay 301, on retracting its armatures, extends the 85 trunk conductors 137 and 138 to the called substation. Relay 2 on retracting its armatures removes ground from conductor 3 to restore the actuated relays of the relay indicating device. 90

At the termination of the conversation the actuation of the supervisory relays 170 and 171 operates in the well-known manner to inform the A operator that the call has terminated. She thereupon removes the 95 plug 104 from the jack 105, which causes the relays 106 and 107 to retract their armatures. This completes a circuit for moving the sequence switch 100 out of position 16 and into position 18. This circuit 100 may be traced from grounded battery, winding of magnet of sequence switch 100, contact 140, armature and back contact of relay 107. In position 18 the down-drive magnet 141 is operated in the well-known 105 manner to restore the selector switch 119 to its normal position. When the switch is restored, a circuit is completed from ground, commutator brush 121, segment 142, contact 144, magnet of sequence switch 100, 110 to grounded battery to move this sequence switch into its normal position. After the restoration of the selector 119, the lamp 306 which was previously shunted, is lighted and the B operator removes plug 316 from 115 the jack 317 of the called line. This operation restores the apparatus associated with the B operator's position, to its normal position. 120

What is claimed is:

1. An apparatus for counting series of current impulses comprising a series of electromechanisms, means for supplying series of current impulses, means for operating the first electromechanism of the series, 125 means effecting the energization of each electromechanism of the series in succession in response to a series of impulses, means operative upon the energization of any electromechanism for deenergizing the 130

preceding electromechanism of the series, and other means operable upon the energization of a particular electromechanism.

2. In a counting device, a series of relays, means for supplying current impulses to control said relays, means for operating the first relay of the series, means effecting the energization of each relay of the series in succession in response to said impulses, 10 means operative upon the energization of any relay for deenergizing the preceding relay of the series, and means operable upon the energization of certain relays for indicating the number of impulses transmitted.
- 15 3. A selection-controlling apparatus comprising a series of electromechanisms, means for supplying series of current impulses to control said electromechanisms, means for energizing a particular electromechanism of the series in response to a series of impulses, 20 said electromechanisms thereafter each controlling the energization of a succeeding and effecting the deenergization of a preceding electromechanism of the series, and mechanism effective upon the energization of a predetermined electromechanism to bring about certain circuit changes in the apparatus to be controlled.

4. A controlling apparatus comprising a series of successively coöperating electromechanisms, means for supplying series of current impulses to control the same, means for energizing a particular electromechanism in response to a series of impulses, each 35 of said electromechanisms thereafter upon energization operating to deenergize a preceding electromechanism of the series, and circuit-controlling means operable upon the energization of a certain one of the electromechanisms.

5. In a controlling system, an incoming circuit, controlling means governed over said incoming circuit, a plurality of outgoing circuits, a plurality of switching means for controlling said outgoing circuits, devices for controlling said switching means including three electromagnetic windings arranged in series, the first electromagnetic winding by its energization controlling the 45 energization of the second electromagnetic winding, the second electromagnetic winding by its energization controlling the energization of the third electromagnetic winding and effecting the deenergization of the first 50 electromagnetic winding.

6. A controlling apparatus comprising a series of successively coöperating electromechanisms, a holding circuit for said electromechanisms having break points controlled by each of said electromechanisms, means for supplying series of current impulses to control said electromechanisms, means for energizing a particular electromechanism, each of said electromechanisms 60 thereafter upon energization operating to

interrupt said holding circuit, and circuit controlling means operable upon the energization of a certain one of the electromechanisms.

7. In a controlling system, means for supplying series of current impulses, an incoming circuit, a plurality of outgoing circuits, a series of electromechanisms arranged to be successively operated to control said outgoing circuits, circuit controlling means responsive to series of current impulses, said circuit controlling means when operated serving to cause the energization of one electromechanism of the series, and when inoperative serving to cause the energization 70 of a succeeding electromechanism of the series.

8. In a controlling system, an incoming circuit, means for supplying series of current impulses over said circuit, a plurality of outgoing circuits, and a series of electromechanisms for controlling said outgoing circuits, controlling means operating in response to series of impulses to control said electromechanisms, said controlling means 85 when operated controlling the actuation of an electromechanism of the series, a succeeding electromechanism of the series being actuated under the joint control of said controlling means and said actuated electromechanism.

9. In combination, means for producing series of impulses of various characteristics, a chain of switching relays, and means responsive to said series of impulses for actuating said relays.

10. In combination, means for producing series of impulses of various characteristics, a chain of switching relays arranged to be actuated in succession, and means responsive 105 to said series of impulses for actuating said switching relays.

11. In combination, means for producing series of impulses of various characteristics, a chain of switching relays arranged to be 110 actuated in succession, means responsive to said series of impulses for actuating said switching relays, indicating devices, and means operating under the control of said switching relays and in response to the impulses of the series for operating said indicating device.

12. In combination, means for producing series of impulses, a chain of switching relays arranged to be actuated in succession, 115 means responsive to said series of impulses for actuating said relays, a plurality of indicating devices, means operating under the control of said switching relays and in response to the impulses of the series to operate said indicating devices in succession.

13. In combination, means for producing series of impulses of various characteristics, a number-indicating device, switching mechanisms for operating said indicating 125 130

device having operating circuits, said switching mechanisms being selectively operated in response to the impulses of a series, and switching relays for controlling 5 said operating circuits, said switching relays being operated in response to series of impulses.

14. In combination, three electromagnetic windings, a circuit normally including two 10 of said windings in series, a second series circuit including said three windings in series, means controlled in part by one of said windings for completing said second series circuit, means controlled in part by 15 a second winding for affecting the deenergization of said first winding and for maintaining said third winding energized, and circuits controlled by said windings.

15. In combination, three electromagnetic 20 windings, means for energizing one of said windings, a series circuit including said windings and controlled by said first winding, means controlled in part by a second winding for maintaining a third winding 25 energized and for deenergizing the first winding, and circuits controlled by said windings.

16. In combination, three electromagnetic

windings, means for energizing one of said windings, a series circuit including said 30 windings and controlled by said first winding, means controlled in part by a second winding for maintaining a third winding energized and for deenergizing the first winding, and a series of electromechanisms 35 arranged to be successively actuated under the control of said third winding.

17. In combination with three electro- 40 magnetic windings controlled by impulses of current from a distant point, means to first actuate one winding, means then operative to simultaneously energize three windings, means then operative to deenergize the first and second of said windings and to maintain said third winding energized, and 45 means then operative to deenergize said third winding, and a series of electromechanisms arranged to be operated in sequence under the control of said electro-magnetic windings, and means to actuate two of said 50 electromechanisms in response to the operation of said electro-magnetic windings.

In witness whereof, I hereunto subscribe my name this 30th day of June A. D. 1917.

EDGAR H. CLARK.
